UNITED STATES PATENT OFFICE.

MARTIN L. PETERSON, OF DETROIT, MICHIGAN.

PIPE-BENDING MACHINE.

Application filed October 29, 1920. Serial No. 420,428.

To all whom it may concern:

- Be it known that I, MARTIN L. PETERSON, a citizen of the United States of America, residing at Detroit, in the county of Wayne 5 and State of Michigan, have invented certain new and useful Improvements in Pipe-Bending Machines, of which the following is a specification, reference being had therein to the accompanying drawings.
- 10 This invention relates to a machine for bending pipe, tubes, wire, rods and the like and more particularly to a machine for forming continuous coils from such materials. An object of the invention is to provide a machine which is adapted to form 15 from a straight piece of pipe or the like of any desired length, a continuous coil of uniform or varying diameter, and further, to form two or more coils of different diameters 20 from a single continuous piece of tubing or the like, with the several coils arranged concentrically, one within the other. A further object is to cheapen and facilitate the 25 operation of bending and coiling stock of any desired diameter or length and securing accuracy and uniformity in the diameter and spacing of the turns of the coils.
- 30 A further object is to enable the operator during a continuous operation of the machine, to vary the diameter of the turns of a coil at will and to accurately graduate a turn of one diameter into another turn of a different diameter during such continuous operation.
- 35 It is also an object of the invention to enable the operator to form any desired number of pieces or lengths of stock into separate coils with a continuous operation of the machine, and to provide simple means for 40 adjusting the machine, which means may be adjusted to vary the product during the continuous operation of the machine.
- 45 It is also an object to provide novel means for feeding and forming the stock whereby the use of separate forming drums or like devices for each size or form of coil is dispensed with, and to provide certain other new and useful features, all as will herein-after more fully appear.
- 50 With the above and other ends in view, the invention consists in the matters herein-

after set forth, and more particularly pointed out in the appended claims, reference being had to the accompanying drawings, in which—

55 Figure 1 is a side elevation of a machine illustrative of the invention;

Fig. 2, a plan view of the same;

Fig. 3 an enlarged sectional detail of the bending rolls and adjacent parts;

Fig. 4 an enlarged transverse section of the carrier and showing a tube in place thereon;

Fig. 5, a detail of a short portion of the carrier in side elevation with a tube in place 65 thereon;

Fig. 6 is a detail illustrative of the manner in which a single coil is formed with evenly spaced turns;

Fig. 7 is a similar view illustrative of the 70 manner of forming concentric coils from a single piece of tubing, and

Fig. 8 is a detail illustrative of the manner in which concentric coils are formed, and showing the same in end elevation, together with the bending rolls.

It has been known that tubing and the like may be bent by running it between rolls, but difficulty has always been encountered in forming by this method coils having turns 80 of uniform diameter and spacing. This uniformity is secured through the manner in which the rolls are placed and the manner in which the tubing is run between them. So far as known to applicant he is the first 85 to devise a machine which will form concentric coils of different diameters from a continuous piece of tubing or the like and with a continuous movement of the stock through the machine.

90 The bending rolls are indicated in the accompanying drawing by the numerals 1, 2, and 3, the roll 1 being supported in a manner to engage the upper side of the tube or other member to be bent and the roll 2 being 95 located below the tube being bent and slightly forward of the roll 1 in the direction of the travel of the tube therebetween. The roll 3 is also located below the tube but to the rear of the roll 1 in the direction of 100 travel of the tube and this roll 3 is carried by a suitable movable support so that it may

be readily raised or lowered. In the operation of the machine this roll is first lowered so that the end of the tube may be inserted between the rolls 1 and 2 and then by raising the roll 3 relative to the rolls 1 and 2 the pipe or tube is given the desired bend as it is forced endwise between the roll 1 and the opposed rolls 2 and 3. The degree of elevation of the roll 3 relative to the rolls 1 and 2 determines the amount of the bend which will be given the tube and this particular arrangement of the roll 1 intermediate the rolls 2 and 3 and the position of the roll 1 rearwardly of the roll 2 gives the setting action or permanent bend which accurately determines the diameter of each turn of the finished coil. The roll 3 simply determines the angle or inclination at which the tube is fed to the rolls 1 and 2 and therefore the amount of the bend which will be put in the tube, but the rolls 1 and 2 give the setting action which takes the spring out of the turn of the coil and gives it a permanent set or bend. The coiled or bent portion of the tube issues from between the rolls 1 and 2 freely, as the tube is forced through between these rolls in contradistinction to being pulled through or fed by a positive drive of one or more of the rolls, and therefore the turns of the coil retain the set or permanent curvature imparted to them by the rolls 1 and 2, which set determines the diameter of the turns and makes them uniform.

In order that the several turns of the coil may be accurately spaced apart and that the coil as it is progressively formed will be projected laterally away from the path of that portion of the tube issuing from between the rolls, a thrust member is placed in a position to engage one side of the tube after it issues from between the rolls so that the formed turn of the coil will be pushed sideways or in a direction longitudinally of the coil, bending the pipe or tube laterally as it is formed and thus, by such bending action determining the spacing of the turns. This thrust member preferably comprises a roll 4 which is rigidly supported in any convenient manner and properly positioned to engage the side of the tube, preferably at a short distance beyond the roll 2.

By so mounting this thrust roll 4 that it may be shifted from one side of the issuing tube to the other, the direction of travel of the coil laterally from its normal path and longitudinally of the coil in either direction, may be changed at will and therefore, as illustrated in Fig. 7, a double coil or a coil of small diameter continuous with a coil of greater diameter and said coils in concentric relation, with the larger coil surrounding the smaller, may be formed. This is accomplished by providing a length of tube or other stock which is great enough to form both coils, then setting the roll 3

so that the coil of the smallest diameter will be formed. After the desired length of coil has been formed, the roll 3 is gradually lowered during the formation of a turn of the coil, thus gradually increasing the diameter 70 of this particular turn until it reaches the diameter at which it is desired to form the large coil, the thrust roll 4 being shifted from one side of the tube to the other at the beginning of the increase of diameter 75 of the turn over the diameter of the smaller coil. This shifting of the thrust roll from one side of the tube to the other will reverse the direction of the travel of the coil laterally or in a longitudinal direction of the coil as 80 it is progressively formed, thus forming the larger coil, outside of and concentrically with the small coil. The space between the inner and outer coils will, of course, be limited by the size of the roll 1 as this roll 85 in forming the outer coil must lie outside the plane of the inner coil which must travel past and over this roll during the formation of the outer coil.

The above described method of coiling a 90 tube, wire, rod, or other similar length of stock is illustrated in Figs. 6, 7 and 8 of the drawing, the supports for the several rolls, and means for adjusting the same being omitted from these figures. 95

In Figs. 1 to 5 inclusive, an organized machine is illustrated and as shown therein the roll 1 is carried by a suitable bracket or support 5 which is pivoted at 6 upon the base 7 of the machine so that said roll may be 100 adjusted toward or from the roll 2 by swinging this bracket upon its pivotal support, in any suitable manner, as by an adjusting screw 8 indicated in dotted lines in Fig. 1. The roll 2 is mounted in suitable bearings 105 upon a fixed support 9 on the base of the machine and the roll 3 is mounted in suitable bearings 10 carried by an adjustable frame 11 which is pivotally supported at one end by the fixed support 9 to swing upon an axis 110 coincident with the axis of the roll 2, that is, one end of this frame is supported by suitable hangers 12 embracing the shaft 13 of the roll 2.

The base 7 of the machine is formed with 115 an inclined track 14 upon which is mounted a carriage 15 and this carriage is provided with suitable rolls 16 at its upper end to engage the underside of the two parallel bars forming the adjusting frame 11 which 120 carries the roll 3. This carriage may be moved along its track in any suitable manner, as by a cable 17 attached thereto and passing over and winding upon a drum 18 mounted in suitable bearings upon the front 125 end of the base of the machine. This drum may be turned in any suitable manner, but as shown in the drawing, its shaft 19 is provided with a suitable clutch 20 for connecting a sprocket wheel 21 thereto so that mo- 130

tion will be imparted to the shaft when the clutch is in operative position through the medium of a sprocket chain 22 engaging the sprocket and passing over a similar sprocket 5 mounted upon the shaft of a suitable motor 23 or other suitable driving means. By operating the clutch 20 the cable 17 is caused to be wound upon the drum 18 and the carriage 15 thus moved up the inclined track, 10 approaching the pivotal support 12 of the adjusting bars or frame 11 which carry the roll 3. By reason of the inclination of the track relative to the bars 11, these bars will be swung upwardly as the carriage moves up 15 the inclined track and thus the roll 3 will be raised relative to the rolls 1 and 2 to regulate the amount of bend which will be given the tubing or other material which is being passed between the rolls.

20 To feed the pipe or other length or lengths of stock endwise between the bending rolls, a suitable endless traveling chain or carrier 24 is provided, said chain comprising a plurality of pivotally connected links to each 25 of which is attached a pair of blocks 25 having formed adjacent sides providing a seat for the tube or other stock 26, as illustrated in Figs. 4 and 5. The links forming this carrier are also provided with teeth 30 27 thus forming a sprocket chain to engage a large driving sprocket or teeth 28 formed on the roll 2 which is mounted upon the shaft 13 and forms the bending roll 2. The sprocket teeth 28 do, in fact, form the face 35 of the bending roll, the carrier chain seating upon said roll between the tube 26 and roll, the roll and chain thus together forming the rotatable bending member over which the tube passes immediately after passing 40 beneath the bending roll 1. Mounted upon the outer end of the shaft 13 of the bending roll, is a sprocket wheel 29 engaged by a sprocket chain 30 which passes over a sprocket on the driving shaft of the motor 45 23 and thus motion is imparted to the carrier chain from the motor, said carrier chain being positively driven thereby. The rear end of the tube or pipe 26 is securely fastened to this carrier chain, in any suitable 50 manner, as by a clip 31, shown in Figs. 1 and 2, and is thereby firmly attached to the chain to be forced endwise thereby between the bending rolls, the power being applied by the chain to the extreme rear end of the 55 tube which is also held seated in the seat blocks 25 of the carrier chain by said clip.

The upper run of this carrier chain is rigidly supported by a swinging frame 32 comprising parallel side bars with a series 60 of rollers 33 mounted between the bars in a position to engage the lower side of this upper run of the carrier chain and form a rigid support therefor. The side bars of this tilting frame 32 also form a support 65 for a sprocket 34 over which the carrier chain runs at its rear end and this tilting frame is pivotally mounted upon bearings 35 which engage and turn about the axis of the shaft 3^a upon which the roll 3 is mounted in the bearings 10. Carried by the 70 extreme forward end of the tilting frame 32 is a roll 36 mounted upon a shaft 37 carried by suitable bearings on this frame and this roll 36 is preferably located substantially in the vertical plane of the axis of 75 the roll 1 so that as the pipe is bent in passing beneath the roll 1 and the rear end of the pipe thereby raised by reason of such bending action, (the roll 3 forming the fulcrum support for the rear end of the pipe), 80 the carrier frame 32 with its carrier chain will be tilted or turned upon the axis of the roll 3 in a like manner and like amount, by reason of the engagement of the roll 36 with the lower side of the bent portion of the 85 tube, or rather, the carrier chain which is interposed between the tube and this roll.

The rear end of the carrier chain is therefore automatically raised to follow the natural upward movement of the rear end of 90 the tube so that it may function to force the tube endwise between the bending rolls by being attached to the rear end of the tube, without putting a bend in the tube between the elevating roll 3 and the rear end of the 95 tube. As the elevating roll 3 forms the fulcrum or support for the tube adjacent the rolls 1 and 2 to direct the tube at the proper angle between these rolls 1 and 2 and thus give the desired bend to the tube, the rear 100 end of the tube must naturally be raised to a divergent relation relative to the frame 11 and therefore by mounting the carrier chain supporting frame 32 so that it may turn freely upon an axis common with that 105 of the roll 3, the rear end of this carrier frame may also rise to a divergent relation to the frame 11, and this upward swinging movement of the carrier frame is made automatic and caused to exactly follow the natural 110 upward movement of the rear end of the tube, by providing the roll 36 upon the free forward end of the carrier frame, which roll rides upon the lower side of the run of the carrier chain which is in firm contact 115 with the bent portion of the tube directly beneath the bending roll 1. A direct force is therefore applied to the rear end of the tube by means of the carrier chain to force the tube endwise between the bending rolls, 120 and the attachment of the rear end of the tube to the carrier chain is made possible by the automatic tilting of the carrier frame with the natural upward movement of the rear end of the tube, so that the full length 125 of the tube may be forced through between the bending rolls by engaging the tube with the carrier chain at the rear end of the tube only, thus making it possible to feed tubes of any desired length continuously through 130

between the bending rolls and have them issue in a bent form freely from between these rolls. A tube which is the full length of the carrier may thus be fed through or 5 tubes or other pieces of stock of greater length or of lesser length than the carrier may be continuously forced through between the bending rolls, a suitable number of detachable clips 31 being provided for securing 10 the piece or pieces of stock in place upon the carrier, and it will also be apparent that instead of the clips 31 other means may be employed for attaching the stock to the carrier chain and such means may engage 15 over the stock in the manner of the clips 31 or may simply engage the rear ends of the several pieces of stock.

The thrust roll 4, previously described, is shown in Fig. 1 as carried by a suitable adjustable bracket 38 which may be supported in any suitable manner, as by the bracket 5, which carries the roll 1. This bracket 38 is preferably so constructed that it may be adjusted to bring the roll into contact with 25 either side of the tube and may be adjusted toward or from the roll 1 to engage various sizes of turns of the coil being formed. It will be noted that the roll 1, as shown in Fig. 1, is of considerably greater diameter in proportion 30 to the rolls 2 and 3 than as shown at 1^a in Figs. 6, 7 and 8, the smaller roll being employed when it is desired to form the double coil shown in Fig. 7 but in bending coils of large diameter with considerable 35 spacing between the turns of the coil, it is not necessary to make the roll 1 of the comparatively small size as illustrated in Figs. 6, 7, and 8 but may be more nearly the size of the rolls 2 and 3, as illustrated in Fig. 1.

40 Tubes or other stock of any diameter in cross section may be bent by means of the machine as illustrated, it being however necessary to adjust the roll 1 relative to the roll 2 upon a change in diameter of the stock being bent as, in order to give the proper set to the bend of the tube, the distance between the peripheral surface of the roll 1 and the effective supporting surface of the roll 2 must be greater than the thickness or cross 50 sectional diameter of the stock being bent, and it is necessary that these rolls 1 and 2 be accurately positioned. Therefore, the roll 1 is made adjustable upon its support 5, in any suitable manner, as by providing a vertical slot 39 in the support to receive the shaft of the roll. This roll 1 may therefore be adjusted vertically relative to the roll 2 and its adjustment laterally toward and from the roll 2 is provided for as hereinbefore described, by mounting the support 5 pivotally upon the base 7.

55 In the operation of the machine, the carriage 12 is first run to the lower end of its track so that the adjusting frame 11 which carries the roll 3 will be in a substan-

tially horizontal position, as shown in Fig. 1 in full lines, or, in a position which is such that the forward end of a tube placed thereon may enter freely between the rolls 1 and 2. When the forward end of the tube is above the roll 2, the carriage 15 is moved up its inclined track, thus swinging the rear end of the frame 11 upwardly and carrying the roll 3 upward relative to the rolls 1 and 2. This upward movement or adjustment of the roll 3 will bend the tube and form a support therefor to guide it, at the proper angle, between the rolls 1 and 2 to give the desired bend to the tube. The carriage 15 is therefore drawn up the incline just sufficiently to elevate the roll 3 to the proper position to guide the tube at the desired angle in order to give the desired bend or set to the tube. At the time of adjustment of the carriage 15, the motor is started and the carrier operated to force the tube endwise between the rolls. The diameter of the turns of the coil being formed during the operation of the machine, may be varied at will by adjusting the carriage 15 along its inclined track. By a continued even adjustment of the carriage 15 relative to the movement of the carrier chain, an even graduation of a turn of the coil from a turn of one diameter to a turn of another diameter may therefore be accomplished, as illustrated in Fig. 8, or a coil of conical form in which the turns uniformly diminish in diameter toward one end of the coil, may be made by a continuous even adjustment 95 of the carriage 15 during the progress of the tube between the rolls throughout the time of forming the entire coil. After the formation of one coil of a certain diameter and desired length, another coil of a greater 100 diameter continuous therewith may be formed with the coil of larger diameter surrounding the smaller coil, as illustrated in Fig. 7 and as previously described, by adjusting the thrust roll 4 upon its bracket 110 38 and by moving the carriage 15 during the formation of one turn of the coil, as previously described, to form a graduated turn connecting the two coils, the adjustment of the roll 4 into engagement with the 115 proper side of the tube after the formation of the smaller coil, causing the turns of the larger coil to lead in a direction opposite to that of the turns of the smaller coil and cause a travel of the large coil during its formation, in a longitudinal direction opposite to that at which the smaller coil moved when it was formed, thus forming the large coil outside of and concentric with the small coil.

120 Obviously other means than the carrier chain, shown in Figs. 1 to 5 inclusive may be employed for forcing the tube endwise between the bending rolls which are preferably plain idler rolls, that is, rolls not 130

positively rotated or driven to feed the tube forward, it only being necessary to provide some means for engaging the rear end of the tube, which means is free to rise with said 5 end of the tube as it moves upwardly under the force of the bending action of the roll 1 which force will tend to swing the rear end of the tube upwardly by reason of the engagement of the roll 3 with the lower side 10 of the tube rearwardly of the roll 1, and it may be noted that it is desirable to have the roll 3 positioned adjacent the roll 1 so that substantially the full length of the tube will be bent to the proper form and in some 15 instances it may be desirable to adjust the roll 3 along the frame 11 and carrier frame 32 to give the desired results. Other means than the carriage 15 may also be employed for raising the rear end of the frame 11 to 20 adjust the roll 3 relative to the rolls 1 and 2 but for heavy work this carriage running upon an inclined track is found to be the preferred means for the purpose as it requires but little power to operate it and gives 25 great accuracy of adjustment. It is also obvious that the adjusting means, such as the carrier 15 and the means for forcing the tube through between the rolls, such as the carrier chain, may be separately and 30 independently operated by power applied thereto in any suitable manner or may be manually operated where the work to be done requires comparatively little power, such as where wires or tubes of small diameter 35 are to be bent.

Obviously other changes in the construction and arrangement of parts within the scope of the appended claims may also be made without departing from the spirit of 40 the invention and I do not therefore limit myself to the particular construction shown.

Having thus fully described my invention what I claim is:

1. A bending machine wherein a plurality 45 of rolls are provided to bend the stock and said rolls are arranged to permit a free transverse movement of the free end portion of the stock, means for feeding the stock to the rolls, said feeding means being free 50 to move transversely with the transverse movements of the rear end portion of the stock.

2. In a bending machine, the combination 55 of a bending roll to engage one side of the stock to be bent, a second bending roll opposed to the first bending roll and set in advance of the first bending roll in the direction of travel of the stock, a third roll to direct the stock to said first and second 60 rolls, and means for feeding the stock end- wise independently of the rolls, said means being free to follow the transverse movements of the rear end portion of the stock caused by the bending action of the rolls.

3. In a bending machine, the combination

of a bending roll to engage one side of the stock to be bent, a second bending roll opposed to the first bending roll and set in advance of the first bending roll in the direction of travel of the stock, a third roll 70 to direct the stock to said first and second rolls, means engaging and supporting the rear end portion of the stock for feeding the same endwise, and means for causing said feeding means to follow the transverse 75 movement of said rear end portion of the stock.

4. In a bending machine, the combination 80 of a bending roll to engage one side of the stock to be bent, a second bending roll opposed to the first bending roll and set in advance of the first bending roll in the direction of travel of the stock, a third roll to direct the stock to said first and second rolls, feeding means adapted to follow the trans- 85 verse movement of the rear end portion of the stock, and means for carrying said feed- ing means and adapted to adjust said third roll relative to said other rolls simulta- neously with the progress of the stock and 90 the bending thereof, to produce a variation in the curvature of the stock issuing from between the rolls.

5. In a bending machine, the combina- 95 tion of a bending roll to engage one side of the stock to be bent, a second bending roll opposed to the first bending roll and set in advance of the first bending roll in the direction of travel of the stock, a third roll to direct the stock to said first and 100 second rolls, means for feeding the stock endwise between the rolls, adjustable means for supporting said third roll, and means for adjusting said adjustable means simulta- neously with the progress of the stock and 105 the bending thereof.

6. In a bending machine, the combina- 110 tion with bending rolls, of means for forcing stock between the rolls to issue freely from between the rolls in coiled form, means for bending the stock laterally as it issues 115 from between the rolls, pivotally supported means upon which one of said bending rolls is mounted, and means for swinging said pivotally supported means upon its pivot to 115 adjust said roll during the production of a turn of the coil for varying the diameter thereof.

7. In a bending machine, the combina- 120 tion of bending rolls, and means for feed- ing stock endwise between the rolls, said means being engaged with the rear end portion of the stock and operated by the bending of the stock to cause said means to follow the transverse movement of the 125 rear unbent end of the stock, which trans- verse movement is caused by the bending of the stock between the rolls.

8. In a bending machine, the combina- 130 tion with bending rolls, of means for ad-

- justing said rolls relatively including a work supporting means and member movable upon an incline to effect said relative adjustment of said rolls and the adjustment 5 of the work simultaneously.
9. In a bending machine, the combination with bending rolls, of means for adjusting one of said rolls including a frame pivotally supported intermediate its ends and upon 10 which the roll is mounted adjacent one end of said frame and means for turning said frame upon its pivotal support.
10. In a bending machine, the combination with bending rolls, of means for adjusting one of said rolls including a pivoted frame upon which said roll is mounted, and means including a member movable upon an 15 inclined way for turning said frame upon its pivot.
11. In a bending machine, the combination with bending rolls, of means for adjusting one of said rolls including a frame pivotally supported adjacent one end and upon 20 which said roll is mounted, and means including a member movable longitudinally of and beneath said frame for raising the free end of said frame.
12. In a bending machine, the combination with bending rolls, of means for adjusting said rolls relatively including a swinging frame, an inclined track beneath said frame, and means movable along said track for swinging said frame.
13. In a bending machine, the combination 25 of bending rolls, an endless carrier for supporting and forcing stock endwise between the rolls and a pivoted track for the upper run of the carrier.
14. A machine as characterized in claim 13 and further characterized in that said track is pivoted to turn upon an axis coincident with the axis of one of said rolls.
15. A machine as characterized in claim 13 and including a pivotally supported frame 30 upon which one of said rolls is mounted and wherein said track is pivotally mounted upon said frame to turn relative thereto and upon an axis coincident with the axis of said roll.
16. A machine as characterized in claim 13 and including a pivotally supported frame upon which one of said rolls is mounted and wherein said track is pivotally mounted upon said frame to turn relative thereto and 35 upon an axis coincident with the axis of said roll, and further including means carried by said track adapted to be operated by the deflection of the stock when bent by said bending rolls, for turning said track upon its pivotal support.
17. A machine as characterized in claim 13 and including a pivotally supported frame upon which one of said rolls is mounted and wherein said track is pivotally 40 mounted upon said frame to turn relative thereto and upon an axis coincident with the axis of said roll, and further including a roll carried by said track and in opposed relation to one of the bending rolls with a portion of the stock being bent by said bending roll interposed between said roll carried by the track and said opposed bending roll.
18. In a bending machine, the combination of a bending roll to engage one side of the stock to be bent, a second bending roll opposed to the first bending roll, a third roll, an endless carrier chain passing over said second and third rolls and adapted to carry the stock to be bent endwise between the bending rolls, means for adjusting said third roll relative to said first and second rolls, and means for driving the carrier chain.
19. A machine as characterized in claim 18 and including a track for the upper run of the carrier chain pivotally supported to turn upon an axis coincident with the axis of said third roll.
20. A machine as characterized in claim 18 and including a pivoted track member for supporting the upper run of the carrier chain, an adjusting frame upon which said third roll is mounted, said frame being pivotally supported to turn upon an axis coincident with the axis of rotation of said second roll, means rotatable upon an axis coincident with the axis of rotation of said second roll and around which said endless carrier passes, means on the free end of the track member around which the endless carrier passes, and means on said track member adjacent its pivotal support opposing said roll to engage said carrier chain and tilt said track member upon its pivot.
21. In a bending machine, the combination of a bending roll to engage one side of the stock to be bent, a second bending roll opposed to the first roll, a third roll for directing the stock to said first and second rolls, a frame member pivotally supported adjacent one end and upon which said third roll is mounted, an inclined track extending longitudinally of said frame member, and a carriage movable along said track between said track and frame member.
22. In a bending machine, the combination of a bending roll to engage one side of the stock to be bent, a second bending roll opposed to the first roll, a third roll for directing the stock to said first and second rolls, a frame pivotally supported at one end upon an axis coincident with the axis of said second roll and upon which said third roll is mounted, a member forming an extended track pivotally supported upon an axis coincident with the axis of said third roll, an endless carrier supported by said track member with its upper run engaging said track throughout the length thereof, an inclined track beneath said frame, a carriage movable along said track and engaging the lower

side of said frame to raise or lower the free end thereof, means to engage the bent portion of the stock issuing from between said first and second rolls and bend said stock laterally, means for adjustably supporting said last named means, and means for driving the endless carrier.

In testimony whereof I affix my signature in presence of two witnesses.

MARTIN L. PETERSON.
